UNITED STATES PATENT OFFICE.

ORLYSTIS M. POTTER, OF LARNED, KANSAS.

COMBINATION-GARMENT.

1,076,390.

Specification of Letters Patent. Patented Oct. 21, 1913.

Application filed January 14, 1913. Serial No. 741,873.

To all whom it may concern:

Be it known that I, ORLYSTIS M. POTTER, a citizen of the United States, residing at Larned, in the county of Pawnee and State 5 of Kansas, have invented certain new and useful Improvements in Combination-Garments, of which the following is a specification.

This invention relates to combination or 10 one-piece garments and while more particularly intended to be used for a combination outside shirt and drawers or nether garment, yet it is applicable to union suits of under-wear and for pajamas.

15 One of the objects of my invention is to provide a combination one-piece garment that may be put on or taken off like a coat-shirt, without placing it over the head and without inserting the feet and limbs. A 20 person can, therefore, change his garment very quickly and without the necessity for removing trousers, shoes or hose, which is a decided advantage especially in warm weather when frequent changes in the clothing 25 are desirable.

Another object of this invention is to provide a garment in which the length of the trunk may be adjusted and in all positions the garment will be symmetrical and the 30 parts will be smooth and comfortable to the wearer.

Other objects and advantages will appear from the following description.

In the accompanying drawings, Figures 1 35 and 2, are perspective views showing a combination garment embodying my invention in position upon a person; Figs. 3 and 8 are perspective views of the garment with each side thrown back to expose the interior construction and show the arrangement of the crotch member; Fig. 4, is a fragmentary front view of the lower part of the garment showing the manner of adjusting the length of the trunk; Figs. 5, 6, and 7, are diagrammatic views of patterns showing the manner 45 of constructing the component parts of the garment; and Fig. 9, is a perspective view showing the rear of the garment.

Fig. 5, shows the right-hand front half 50 of the combination garment and the opposite or left-hand front piece is symmetrical thereto but reversed in shape, one part having button-holes 2, and the other piece carrying the cooperating buttons, the upper part 1^a 55 above the waist-line ~~or~~ ^a, constituting the

shirt portion and the lower part 1^b, constituting the nether portion or drawers.

Fig. 7, shows the left hand back piece or half and the right-hand back-piece is the same reversed. Fig. 6, shows one of the 60 back-pieces with the undercrotch member 4 separated from the nether part. By making the crotch-members of separate pieces of cloth and sewing them along their vertical edges to the main back pieces, I am 65 enabled to cut both front and back pieces from straight pieces of material which is advantageous both from the standpoint of economy and because, when made of striped material, the stripes will run straight up and down through the shirt portion. This construction also causes the strains to which the garment is subjected in the laundry to be longitudinal of the weave of the fabric. The 70 crotch pieces 4, which form the under-crotch 75 and inner leg parts, may be cut so that the stripes will conform to the main leg portions when brought into position upon the wearer.

When the parts are sewed together, a combination garment of shirt and drawers is 80 formed which is of coat-form, open from top to bottom, as illustrated in Fig. 3, and the crotch-member 4, formed of the two parts sewed together along the top curved edge, 85 projects forwardly from the intersection of the bifurcated lower portion of the back members, curving upwardly as shown. In this position, the garment may be put on in the same manner as a coat, the arms being 90 passed through the sleeves 6, and the front portions being then brought together and buttoned, with the crotch-member passing beneath the crotch and projecting in front.

The trunk length is adjusted to the desired length by buttoning the button-hole 2^c 95 in the tip or front end of the crotch-member, over either the button 3^a or the button 3^b which are just below the waist-line. The leg portions are then closed by inserting the buttons 3^c through the button-holes 2^a or 2^b. 100 The adjustment of the length of the trunk is shown in the detail view Fig. 4. It will be observed that when the end of the crotch-member is lifted from the lower button 3^b to the upper button 3^a the crotch of the garment is raised, thereby shortening the trunk. A larger number of button-holes may be employed if desired. This adjustment of the trunk-length not only adapts the same 105 garment to different sizes, thereby reducing 110

the different sizes of garments required to be carried in stock by the retail merchant, but this means of adjustment also provides a means of allowing for shrinkage in the fabric during use, which is liable to occur in non-elastic materials. The pull upon the crotch-member is always upon a median line and consequently symmetrical, there being no tendency to become tighter upon one side than the other. By observing the relation of parts in changing from the full-line lower position to the dotted-line upper position of adjustment, it will be seen that the leg portions accommodate themselves to the changes in the trunk-length by a slight change in the girth or leg-opening and without any folding or wrinkling, remaining at all times smooth and comfortable. The importance of this feature will be evident and is one of the advantages in my present invention.

As mentioned above, the garment is put on and taken off in the manner of a coat without inserting either head or feet and a change of garments may accordingly be made very quickly. When the garment is on the wearer, the entire front of the crotch tab-member may be loosened and freed by merely unbuttoning the one button at the crotch front and the seat can then be readily cleared; by further unbuttoning the button or buttons along one leg, that leg and the crotch portion may be shifted to the opposite side; and by unbuttoning both leg portions the entire bifurcated portion may be lifted or withdrawn to the rear. These functions will be appreciated by those familiar with the usual difficulties accompanying the use of combination garments.

In garments of this type it is desirable that the shirt portion should remain smooth above the top of the trousers and not pucker or fold over the belt after stooping or leaning over. I have therefore shown this garment provided with the plait or fold 8, below the waist-line, in Figs. 3, 6 and 7, such as disclosed in my Patent No. 973,299, granted October 18, 1910. It is to be understood, however, that the improvements disclosed herein, may be used with a plain back, as illustrated in Fig. 9, or with any other style of back that may be desired. Furthermore, the nether garment may be full length instead of knee-length.

It is sometimes desirable to be able to use my coat-type combination garment merely as a shirt with the usual separate drawers. I may, therefore, provide an auxiliary button below the waist-line but above the seat, to which the button-hole 2° of the crotch tab-member may be buttoned. This button may be placed on the inside of the garment or it may be placed on the outside at the back, and in the latter case, the crotch member will be reversed and folded back against

the outside of the garment. In Fig. 8, I have illustrated the button 3° upon the inside of the garment and the crotch tab-member buttoned thereto. In this arrangement the garment may be used as an ordinary coat-shirt, the lower shirt part being bifurcated at the inside of both front and back portions so that one-half of the shirt will divide and pass down each trouser leg. This arrangement will accommodate the man who may upon occasions wish to change from the one-piece combination suit to two-piece underwear. Inasmuch as shirting material is light in weight and the arrangement as disclosed in Fig. 8, is split up the back, there will be no bunching at the crotch and the garment will be convenient and comfortable.

I have described in detail the particular construction illustrated in the accompanying drawings for the purpose of disclosing an embodiment of my invention, but I am aware that changes may be made therein without departing from the spirit of my invention. I have referred to the advantages that accrue from cutting the entire length of the front and back pieces of the garment from a single piece of material, but these pieces would still be regarded as integral parts if they were made up of separate pieces sewed together. The crotch-member may be cut from a single piece of material with the corresponding back pieces as shown in Fig. 7, or they may be formed separately as in Fig. 6, and then be sewed to the back pieces.

I claim:

1. A combination garment comprising in a one-piece suit, a shirt and drawers open throughout the front from the top to the bottom of the garment upon a median line, the back being bifurcated below the crotch, a bifurcated crotch-member closed at the crotch line and separated therebelow, and secured to the bifurcated back portion of the garment and adapted to project through said front opening, and means for securing the separate edges of the front portions of said crotch-member respectively to the opposite margins of the front portion of the garment upon the inner side of each leg, thereby forming leg closures or drawers.

2. A combination garment comprising in a one-piece suit, a shirt and drawers open throughout the front from the top to the bottom of the garment upon a median line, a bifurcated crotch-member closed at the crotch line and separated therebelow, and secured to the back portion of the garment and adapted to project through said front opening, means for securing the separated front edges of said crotch-member respectively to the opposite margins of the front portion, thereby forming leg closures or drawers; and means for adjusting the height

- of the crotch-member with respect to the shirt portion.
3. A combination garment, comprising in a one-piece suit, a shirt and drawers open in front upon a median line from the shirt-neck to the bottom of the drawers, a bifurcated crotch-member secured to the back of the garment from the crotch to the bottom of the garment thereby forming a completely closed garment in the rear, said crotch-member projecting through said front opening, means for securing the upper end of the projecting part of said member to the shirt portion above the crotch, the separated parts of said bifurcated crotch member overlapping the opposite margins of the front portion upon either side of the opening upon the inner side of each leg, thereby forming leg closures or drawers.
4. A garment comprising in a one-piece suit, a shirt and drawers, a crotch-member closed along the crotch line and separated therebelow, and secured to the rear portion of the garment and projecting through the crotch, and means for securing the front end of said crotch-member to the shirt portion above the crotch at different elevations to thereby adjust the height of the crotch-member.
5. A garment comprising in a one-piece suit, a shirt and drawers, open in front upon a median line from the shirt-neck to the knees, a bifurcated crotch-member closed along the crotch line and separated therebelow, and secured to the rear portion of the garment and extending into the opposite leg parts, said member projecting through said front opening, and means for securing the front end of said member to the shirt portion above the crotch.

In testimony whereof I affix my signature in presence of two witnesses.
